DETACHABLE SECURING MECHANISM FOR
VENETIAN BLIND LIFTING CORDS

Pascal Machroll, Oak Park, Ill.

Application April 24, 1948, Serial No. 23,044

5 Claims. (Cl. 160—173)

1

My invention relates to Venetian blinds and more particularly to an improved construction for suspending the lifting bars thereof from the lifting cords.

Venetian blinds conventionally include a series of spaced horizontal slats extending between two or more guide tape assemblies. Each guide tape assembly includes two vertical portions between which bridging tapes extend at equally spaced vertical distances, which bridging tapes act to sustain the slats in spaced horizontal positions when released. A lifting bar is attached to the guide tapes at the bottom of the blind and, in addition, is independently supported from two or more lifting cords which usually extend in vertical alignment with the guide tapes. When the blind is raised, the lifting cords are pulled upwardly, thereby lifting the lifting bar and successively picking up the slats as the lifting bar reaches the horizontal level of each.

Heretofore, each lifting cord has been attached to the lifting bar by means of a knot which engages the wall defined by the enlarged portion of an opening extending vertically through the lifting bar to receive the lifting cord. Usually, the guide tapes extend underneath the bar to hide the knotted end of the cord to present an attractive appearance. This structure presents a serious problem when it is desired to clean the Venetian blind since it is generally impossible thoroughly to clean the blind without removing the various slats therefrom. Since removal of the slats requires withdrawal of the lifting cords therefrom, such cleaning has heretofore required removal of the guide tapes from the lifting bar, together with untying of the knot to permit withdrawal of the lifting cord.

In accordance with the present invention, the foregoing difficulties heretofore associated with Venetian blinds are overcome by providing a readily removable assembly for attaching the lifting cords to the lifting bar. By opening the assembly of the present invention, each lifting cord may be withdrawn from the slats and a thorough cleaning conducted without the necessity of removing the guide tapes from the lifting bar or otherwise disassembling the unit.

It is, therefore, a general object of the present invention to provide an improved readily removable assembly for detachably securing a lifting cord to the lifting bar of a Venetian blind.

Further, it is an object of the present invention to provide an improved assembly for detachably securing a lifting cord to the lifting bar of a Venetian blind, which assembly incorporates a

2

fastener attached to the lifting cord and which is capable of passing through the cord openings of the slats.

Yet another object of the present invention is to provide an improved assembly for detachably securing a lifting cord to the lifting bar of a Venetian blind and which includes hooking elements permitting ready removal of the fastener when shifted and tilted relative to the lifting bar.

A still further object of the present invention is to provide improved fastener and bracket elements for use in an assembly for detachably securing a lifting cord to the lifting bar of a Venetian blind.

It is yet another object of the present invention to provide an improved readily removable assembly for detachably securing a lifting cord to the lifting bar of a Venetian blind and which may readily be installed on a conventional Venetian blind.

My invention further resides in features of construction, combination, and arrangement whereby an improved assembly for detachably securing a lifting cord to the lifting bar of a Venetian blind is provided which is simple and inexpensive in construction and reliable in operation and does not detract from the pleasing appearance of the blind.

The novel features which I believe to be characteristic of my invention are set forth with particularity in the appended claims. My invention, itself, however, both as to its organization and method of operation, together with further objects and advantages thereof, may best be understood by reference to the following description taken in connection with the accompanying drawing in which:

Figure 1 is a fragmentary view of a portion of a Venetian blind assembly incorporating the mechanism of the present invention;

Figure 2 is an enlarged fragmentary side elevational view of the assembly of Fig. 1;

Figure 3 is a fragmentary cross-sectional view through axis III-III, Fig. 2;

Figure 4 is a cross-sectional view through axis IV-IV, Fig. 2;

Figures 5, 6, and 7 are side elevational top plan, and end elevational views respectively of the fastener of the present invention in the split or opened condition;

Figure 8 is a cross-sectional view through the axis VIII-VIII, Fig. 5;

Figure 9 is a top plan view of the bracket of the present invention; and

Figure 10 is an enlarged side elevational view of the assembly of the present invention and showing how the fastener is removed from the bracket thereof to detach the lifting cord from the lifting bar.

Referring now to Figs. 1, 2, and 3, there are shown fragmentary views of a Venetian blind incorporating the assembly of the present invention. This blind includes a bottom or lifting bar 24 extending in a horizontal direction and which is supported by the spaced vertical lifting tapes 26 and by the lifting cord 25. A plurality of horizontal spaced slats 29 are supported from the tapes 26 by the cross members or bridges 28 which comprise cloth tapes secured thereto or woven therewith. These bridges are uniformly spaced on the tapes 26 to support the slats 29 in uniform vertical spacing.

Each slat 29 is apertured, as indicated at 30, to receive freely the lifting cord 25 so that it may 20 be raised and lowered without directly moving the slats. However, as the lifting bar 24 is raised by the lifting cord 25, the top of the lifting bar 24 engages the lowermost bridge tape 28 to raise the lowermost slat 29, and each slat, in turn, engages the bridge supporting the slat above it successively to lift the slats.

While the accompanying drawing shows only a single set of guide tapes 26 and a single lifting cord 25, it will be understood that normally at 30 least two of these assemblies are used to sustain and lift the lifting bar 24 and the slats 29.

The assembly of the present invention includes a fastener portion 11 pinched on the end portion of the cord 25 and which is detachably secured to the bracket 12 which, in turn, is attached to the lifting bar 24.

The construction of the fasteners 11 may be understood by reference to Figs. 5, 6, 7, and 8. As will be evident from Fig. 5, the fastener comprises two semi-cylindrical shell portions 15 and 16 defining a split barrel when compressed together. These semi-cylindrical portions terminate in inwardly extending teeth 13 and 14 respectively, which are best seen in the top plan view of Fig. 6. A bridge portion 19 extends between the opposite ends of the semi-cylindrical portions 15 and 16 and defines the ears 17 extending in opposite directions in a plane perpendicular to the axis of symmetry of the fastener.

The fastener 11 may be stamped from relatively thin sheet metal and then formed to the shape indicated in Figs. 5, 6, 7, and 8, thereby forming a unitary structure. Preferably, it is made of relatively soft steel. When it is desired to attach the fastener to the end of the lifting cord 25, the semi-cylindrical portions 15 and 16 are squeezed together by a pliers or a similar tool to cause teeth 13 and 14 to bite into the cord 25 and securely hold the fastener to the cord.

It will be observed that the diameter of the semi-cylindrical shell portions 15 and 16 of the fastener 11 is sufficiently small to permit the cord 25 to be withdrawn without the fastener 11 engaging the edges of the openings 30 provided in the slats 29 to receive cord 25. Moreover, the openings 30 are elongated in the direction normal to the view of Fig. 2 to provide ample space to pass ears 17.

The bracket 12 is preferably stamped from soft sheet steel. It includes a flat base portion 31, Fig. 9, having an opening 32 to receive the wood screw 23, Fig. 2, by which it is attached to the lifting bar 24. The corners of the base portion

31 are bent downwardly to define sharp points 21 which securely lock the bracket 12 to the lifting bar 24 and prevent rotation of bracket 12 about screw 23.

5 A pair of spaced prongs 20 extend from the base portion 31 of the bracket 12. These prongs are spaced from each other and extend in aligned relationship to define a slot 33, Fig. 9, of sufficient width to receive the bridge portion 19, Fig. 7, of the fastener 11. However, the prongs 20 are spaced sufficiently close together to overlie the ears 17, Fig. 7, of the fastener 11 when the bridge portion 19 thereof is received within the slot 33.

As best shown in Fig. 10, the prongs 20 are each bent-over to define aligned hooks against which the ears 17 rest. These hooks permit rocking movements of the lifting bar 24 relative to the fastener 11 to maintain the cord 25 in a proper centering position as the lifting bar 24 is tilted.

In applying the bracket 12, the screw 23 is fastened in position to align the slot 33 with the cord 25 to cause fastener 11 naturally to assume an upright position.

25 As shown by the dotted lines in Fig. 10, the fastener 11 may be detached from the bracket 12 by tilting the fastener 11 to alignment with the end portion of the prongs 20 and then shifting the fastener 11 to a position wherein the ears 17 no longer underlie the prongs 20. Alternatively, the lifting bar 24 may be tilted to align the ends of the prongs 20 with the bottom portion of the fastener 11 and then shifted to withdraw the bridge portion 19 and fastener 11 from the slot 33 of the bracket 12.

With the assembly of the present invention, it is very simple to convert a conventional Venetian blind to an improved Venetian blind wherein the lifting cords are detachably secured to the lifting bar. This may be done with the blind fully extended and with the guide tapes 26 serving to support the lifting bar 24. The cord 25 is detached from the lifting bar 24, as, for example, by severing the bottom portion thereof. The bracket 12 can then be screwed to the lifting bar 24 and fastener 11 clamped over the end portion of the lifting cord 25 to cause the teeth 13 and 14 securely to grip that cord. The assembly is completed by sliding the bridge portion 19 of the fastener 11 into the slot 33.

55 Figure 4 is a cross-sectional view of the cord 25 at the point the teeth 13 and 14 bite into that cord when the fastener 11 is closed.

50 While I have shown a particular embodiment of my invention, it will of course be understood that I do not wish to be limited thereto since many modifications both in the various parts and in their cooperative structure may be made without departing from the spirit and scope of my invention. I, of course, contemplate by the appended claims to cover any such modifications as fall within the true spirit and scope of my invention.

55 What is claimed is:

60 1. A fastener for use with a Venetian blind of the type having a lifting cord and a lifting bar having a bracket defining prongs spaced from each other and from said bar, said fastener comprising a split barrel having teeth at one end to bite into a cord, and a bridge on the opposite end, said bridge having ears extending in opposite directions in a horizontal plane and adapted to underlie the prongs and engage the prongs to lift said bar.

70 2. A bracket for use with a Venetian blind hav-

ing a lifting bar and a lifting cord terminating in a fastener having ears extending in opposite directions in a plane parallel to said bar, said bracket comprising a plate having an opening to receive a screw for attachment to a lifting bar and locking spurs to bite into said bar, said bracket further having spaced bent-over prongs curved upward centrally of their lengths and defining aligned hooks adapted to overlie ears on a fastener for engagement therewith to lift said bar.

3. An assembly for detachably securing a lifting cord to the lifting bar of a Venetian blind to raise said bar, said assembly comprising a fastener, said fastener comprising a split barrel having teeth at one end to bite into a cord and a bridge at the opposite end, the bridge of said fastener having ears extending in opposite directions in a horizontal plane, and a bracket adapted to be attached to a lifting bar for cooperative engagement with said fastener, said bracket comprising a plate having an opening to receive a screw for attachment to said bar and locking spurs to bite into said bar, said bracket further having spaced prongs defining a slot to receive said bridge of said fastener and bent over to define aligned hooks curved upward centrally of their lengths to overlie said ears for engagement therewith to lift said bar. 25

4. In an assembly for detachably securing the lower end of a lifting cord to the lifting bar of a Venetian blind, a fastener adapted to be at-

tached to the end of a cord and defining a pair of ears extending in opposite directions in a horizontal plane, and a bracket adapted to be attached to a lifting bar and having spaced bent-over prongs defining aligned hooks curved upward centrally of their lengths to receive said fastener and overlie the ears thereof to sustain said bar.

5. In an assembly for detachably securing the lower end of a lifting cord to the lifting bar of a Venetian blind of the type having spaced slats with cord-receiving openings, the assembly comprising a fastener adapted to be attached to the end of a cord and defining ears extending in opposite directions in a horizontal plane, said fastener being of size capable of passing through said openings, and a bracket adapted to be attached to a lifting bar and having prongs curved upward centrally of their lengths and spaced from each other and from said bar defining a slot to receive said fastener and overlie the ears thereof to sustain said bar. 10 15 20
